(57) **CLAIM**

The ornamental design for the combined card wallet and phone holder, as shown and described.

DESCRIPTION

FIG. 1 is a front, right, and bottom perspective view of the combined card wallet and phone holder showing my new design in a folded configuration;

FIG. 2 is a rear, left, and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and bottom perspective view thereof but showing an alternate position, where a piece of card is pulled out of the wallet;

FIG. 10 is a front, right, and bottom perspective view thereof but shown in use with an unclaimed phone feature;

FIG. 11 is a perspective view of the combined card wallet and phone holder in an unfolded configuration, shown in use with an unclaimed phone feature; and,

FIG. 12 is a perspective view of the combined card wallet and phone holder in an unfolded configuration, shown in use with an unclaimed phone feature.

The broken lines in the drawings depict portions of the combined card wallet and phone holder that form no part of the claimed design. The broken lines showing of a phone feature, in FIGS. 10-12, illustrate environmental structures that form no part of the claimed design.

1 Claim, 12 Drawing Sheets
